UNITED STATES PATENT OFFICE.

CHARLES MEHLIN, OF FORT LEE, NEW JERSEY.

PIANO-PEDAL.

1,079,945.

Specification of Letters Patent.

Patented Dec. 2, 1913.

Application filed December 10, 1912. Serial No. 725,973.

To all whom it may concern:

Be it known that I, CHARLES MEHLIN, a citizen of the United States, residing in Fort Lee, in the county of Bergen, in the State of New Jersey, have invented certain new and useful Improvements in Piano-Pedals, of which the following is a specification, reference being had to the accompanying drawings, forming a part hereof.

This invention relates to pedals for pianos and has for an object to improve generally their construction and appearance. More particularly it is sought to provide a pedal which will not become unsightly by wear. Hitherto piano pedals have been formed throughout their exposed portions with relatively broad and flat upper surfaces which quickly become worn and unsightly. In accordance with the present invention the pedal has a relatively broad and flat surface at its forward end but is tapered to the rear and brought to an edge between two convex sides, being in cross-sectional form, an inverted V-shaped member. The ball of the performer's foot rests upon and wears the extreme forward portion of the pedal but the forward portion of the foot rests upon the edge between the convex surfaces, so that the wear is confined to the edge. By reason of the high lights on the highly polished convex surfaces, which are not subject to wear, this edge always appears as a line when viewed from any angle and the whole pedal accordingly retains its new and attractive appearance for a long time and does not soon become unsightly.

The invention will be more particularly described with reference to the accompanying drawings in which—

Figure 1 is a view in perspective of a grand piano provided with pedals constructed in accordance with the present invention. Fig. 2 is a plan view on an enlarged scale of a pedal embodying the invention. Fig. 3 is a view thereof in side elevation. Fig. 4 is a view taken on the plane indicated by the line 4—4 of Fig. 3. Fig. 5 is a view taken on the plane indicated by the line 5—5 of Fig. 3. Fig. 6 is a view taken on the plane indicated by the line 6—6 of Fig. 2.

While it will be understood that the application of the improved pedal is not limited to pianos of the grand type, it has been found convenient to illustrate this type of piano in the accompanying drawings.

On the piano *a* are pivotally mounted the pedals *b* usually three in number by suitable transverse studs *b'*. Each of these pedals has at its rearward portion suitable means, 60 means of which the pedals may be operatively connected to the respective devices of the piano, as will be understood by those skilled in the art. 65

Each of the pedals *b* may be formed in horizontal section of any desired outline, the present invention not being directed to this feature of their construction. The exposed portion of the pedal *b* has at its forward end a relatively flat and broad upper surface, generally designated by the reference character *b*³, adapted to have rested thereon the ball of the performer's foot. As is shown particularly in Fig. 2, however, the 75 surface of the pedal tapers upwardly to the rear and is formed with two convex surfaces *b*⁴ disposed angularly each to each and meeting to form an edge *b*⁵ which is engaged by the forward portion of the performer's foot. 80 As appears from Figs. 4, 5 and 6, the portion of the pedal last referred to is V-shaped in cross-sectional form so that the wear thereon is confined to the edge and does not affect the character of the convex surfaces. 85 The latter, of course, are preferably highly polished and, being free from wear, retain their polished condition and serve to reflect the light so that the condition of the edge itself is not apparent when viewed from any 90 angle and the pedal accordingly retains its new and attractive appearance. 90

The general outline of the edge *b*⁵ in longitudinal vertical section may be of any form desirable, although preferably it describes a curve, such that the wear caused by the frictional contact of the performer's foot will be distributed uniformly over its entire length. 95

In carrying out the invention it will be understood that it is desirable to have the angle between the convex surfaces *b*⁴ as small as possible, but this angle must necessarily be relatively large at the forward portion of the pedal where the relatively broad and flat upper surface *b*³ commences to taper rearwardly. The general character of the pedal in cross sectional form is clearly indicated in Figs. 4, 5 and 6 and it has been found that a pedal having the general proportions therein illustrated presents an attractive appearance when new and embodies 105 110

all of the advantages resulting from the present invention, as more particularly pointed out hereinbefore. It is to be understood that the exact proportions, however, 5 may be varied without departing from the spirit of the present invention so long as the pedal is constructed generally in accordance with the terms of the claims hereto appended.

10 What I claim is:

1. A piano pedal having the portion which is exposed to sight and wear formed with convex surfaces on opposite sides of a single upper edge on which rests the 15 performer's foot when the pedal is in use.

2. A piano pedal having at its outer end a relatively broad and rounded upper sur-

face, tapered toward its inner end to form a single edge on which rests the performer's foot when the pedal is in use.

3. A piano pedal having at its outer end a relatively broad and flat upper surface and formed to the rear thereof with two convex faces disposed angularly each to each and meeting in a single edge on which rests 25 the performer's foot when the pedal is in use.

This specification signed and witnessed this 4th day of December A. D., 1912.

CHARLES MEHLIN.
